UNITED STATES PATENT OFFICE

2,595,128

ROCK DRILL

John C. Curtis and Elmer G. Gartin, Claremont,
N. H., assignors to Joy Manufacturing Company,
a corporation of Pennsylvania

Application May 4, 1946, Serial No. 667,384

12 Claims. (Cl. 121—7)

1

This invention relates to rock drills and more particularly, but not exclusively, to improvements in the fluid distributing means and drill steel rotation means of a pressure fluid actuated hammer rock drill.

An object of the present invention is to provide an improved pressure fluid actuated rock drill. Another object is to provide an improved drill steel rotation means for a hammer rock drill. Still another object is to provide an improved fluid distributing means for a rock drill embodying an improved fluid conducting passage arrangement. A further object is to provide an improved drill steel rotation means embodying an improved roller ratchet mechanism associated with a rifle bar. A still further object is to provide an improved steel rotation means embodying a rifle bar having fluid distributing passages associated therewith. Yet another object is to provide an improved inlet and exhaust passage arrangement for a hammer rock drill. Still another object is to provide an improved hammer rock drill of the type known as a plug drill and embodying automatic rotation mechanism for the drill steel. A further object is to provide an improved rock drill having a novel arrangement and combination of parts. These and other objects and advantages of the invention will, however, hereinafter more fully appear in the course of the following description and as more particularly pointed out in the appended claims.

In the accompanying drawings there is shown for purposes of illustration one form which the invention may assume in practice.

In these drawings:

Fig. 1 is a side elevational view of the improved rock drill.

Fig. 2 is a central longitudinal vertical sectional view taken through the improved rock drill on line 2—2 of Fig. 1.

Fig. 3 is a detail horizontal sectional view taken on line 3—3 of Fig. 2.

Fig. 4 is a central longitudinal vertical sectional view taken substantially on line 4—4 of Fig. 2, showing the moving motor parts in a different position.

Fig. 5 is a cross-sectional view taken substantially on line 5—5 of Fig. 4.

Fig. 6 is a cross-sectional view taken substantially on line 6—6 of Fig. 4.

Fig. 7 is a cross-sectional view taken substantially on line 7—7 of Fig. 4.

Fig. 8 is a front face view of the valve box.

Fig. 9 is a rear face view of the valve box cover.

2

Fig. 10 is a perspective view of the fluid distributing valve.

In this illustrative construction, the improved rock drill, generally designated 1, is of the type known as a hand-held plug drill for drilling plug and feather holes. It will be evident, however, that the various features of the invention may be incorporated in rock drills of other types.

The improved rock drill comprises a motor cylinder 2 having a bore 3 containing a reciprocable hammer piston 4. The hammer piston has a rear piston head 5 and a reduced forward cylindric extension or striking bar 6 slidingly guided in a reduced front bore 7 in the integral front head or front cylinder portion 8 of the motor cylinder. The forward end of the piston striking bar is formed with an axial bore 9 in which is pressed or otherwise secured a cylindrical striking block or plug 10 of relatively hard metal, and this striking block is adapted to strike against the shank 11 of a conventional plug drill steel 12. The piston is formed with an enlarged axial chamber 13 opening through the rear side of the piston head, and this chamber is connected by a reduced axial bore 14 to the rear end of the bore 9. When the drill is dismantled, a suitable instrument, such as a rod or bar, may be inserted through the chamber 13 into the bore 14 into engagement with the striking block 10 so that the latter may be driven out of the bore 9 for replacement purposes.

Improved rotation means for the drill steel, operated by the hammer piston, is provided, comprising a rotatable rifle bar 15 having spiral grooves slidingly interlocked with the spiral lugs of a rifle nut 16 secured within the rear end of the piston chamber 13 as by threading at 17. Formed in a rear head 18 of the motor cylinder is an eccentric bore 19 (see Fig. 5) having mounted therein for free rotation an annular reaction member in the form of a sleeve-like annulus 20 having a smooth internal peripheral surface 21. Also arranged in the bore 19 within the annulus 20 is a cylindrical member 22 formed integral with the rifle bar 15. The cylindrical member 22 has a reduced circular bearing portion 23 journaled in an axial bore 24 in the rear cylinder head 18. Arranged in the space 25 between the eccentrically disposed inner and outer cylindrical surfaces of the members 20 and 22 is a gripping element in the form of a gripping roller 26 of cylindrical form, having midway between its ends an annular circumferential groove 27. Also arranged in the space 25 is a stationary pin 28 and acting on this pin and engaged in the roller groove 27 is a

loop-bent spring 29 for constantly urging the roller toward frictional gripping engagement with the inner and outer cylindrical surfaces of the members 20 and 22. When the cylindrical member 22 is rotated in a counterclockwise direction, as viewed in Fig. 5, the roller 26 wedges between the inner and outer surfaces of the members 20 and 22 to lock these members together and to expand or spring slightly the sleeve 20 into tight frictional engagement with the walls of the bore 19 of the rear cylinder head, thereby to hold the rifle bar 15 against rotation. When the cylindrical member 22 is rotated in a clockwise direction, as viewed in Fig. 5, the roller 26 moves against the pressure of the spring 27 out of gripping engagement with the inner and outer surfaces of the members 20 and 22, thereby to permit the rifle bar 15 to rotate. The sleeve-like member 20 against which the roller reacts may freely rotate in the bore 19 relative to the rear cylinder head when the gripping roller is released so that the gripping roller may engage the inner cylindrical surface thereof at different points to reduce concentrated wear. It will thus be seen that when the hammer piston moves rearwardly in the cylinder bore, the gripping roller holds the rifle bar against rotation so that the spiral lugs on the rifle nut 16 engaging the spiral groove of the rifle bar 15 cause the hammer piston to rotate. When the hammer piston moves forwardly in the cylinder bore to effect its working stroke, the gripping roller automatically releases to permit free rotation of the bar so that the piston moves forwardly without rotation to strike on unimpeded blow on the drill steel shank. For transmitting the rotary motion of the drill steel, there are provided straight longitudinally extending grooves or splineways 31 on the piston striking bar 6, and these grooves have sliding interlocking engagement with straight lugs or splines 32 formed integral with a rotatable chuck sleeve 33, the latter being rotatably mounted in a bore 34 in a front chuck housing 35. Pressed or otherwise fixed in a bore 36 in the rotatable chuck sleeve 33 is a chuck bushing 37 having an axial bore 37' for receiving the round shank 11 of the drill steel. The bushing 37 has spaced projections 38, 38 at its forward side having inner plane surfaces 39 engaging parallel opposed sides of the square body of the drill steel 12 (Fig. 7). It is accordingly evident that as the hammer piston reciprocates to actuate percussively the drill steel, the latter is concurrently intermittently rotated. The interior of the chuck sleeve in advance of the piston striking bar is vented through the clearance space in the chuck bushing bore around the round shank of the drill steel, in an obvious manner.

Now referring to the improved fluid distributing means for the drill motor, it will be noted that arranged in an enlarged bore 40 in axial alignment with the cylinder bore and formed in the rear head block 41 is a valve box cover 42. Also arranged in the bore 40 and abutting the rear face of the cover 42 is a valve box 43. A dowel pin 44 fixed in aligned holes in the cylinder and the rear cylinder head engages registering grooves in the rear head block 41 and the valve box parts 42, 43 to hold the parts against relative rotation and in alignment. The pin 28 is fixed in the parts 18 and 42. The valve box cover 42 has a forwardly projecting cylindrical portion 45 received in a bore 46 in the cylindrical member 22, and this cylindrical portion provides an additional bearing support for the rifle bar. Formed

in the valve box 43 is a valve chamber 47 in which a reciprocating fluid distributing valve 48 of the circular plate or disk type is arranged and the valve box parts have annular seating surfaces 49 and 50 at the bottom and top of the valve chamber against which the opposite plane surfaces of the valve are adapted to engage. There is a restricted clearance space between the outer periphery of the valve and the walls of the valve chamber to permit metered flow of pressure fluid past the valve. The front valve box cover 42 has an axial passage 51 extending through the cylindrical bearing portion 45 and communicating with the forward side of the bore 46, and the bearing portion 23 of the rifle bar has passages 52 for connecting the bore 46 with the rearward ends of certain of the spiral grooves of the rifle bar and through these grooves with the rear end of the cylinder bore. The rifle bar has an axial passage 53 for connecting the forward side of the bore 46 with the chamber 13 within the hammer piston. The valve box 43 has an axial passage 54 connecting the valve chamber 47 with a recess 55 in the rear face of the valve box 43, and this recess is closed at its upper side by the rear wall 56 of the bore 40 in the rear head block 41. The recess 55 is connected by ports 57 with passages 58 and 59 in the valve box cover 42 and the rear cylinder head 18, and the passages 59 communicate with longitudinal passages 60 in the walls of the motor cylinder 2, these latter passages communicating through ports 61 with the forward end of the cylinder bore. Pressure fluid may be supplied to the valve chamber from a fluid supply pipe 63 threaded secured to a plug 64 in turn threaded at 65 in a combined inlet and exhaust block 66. The block 66 has a curved inner surface 67 which fits the outer cylindrical surface of the motor cylinder, and the block is permanently secured to the side of the cylinder as by welding. The plug 64 acts on a rubber gasket 68 to hold the latter in tight sealing engagement with the curved outer surface of the cylinder. The plug 64 has a passage 69 which connects the supply pipe 63 with a passage 70 through the gasket, the latter communicating with a passage 71 in the adjacent cylinder wall. The passage 71 is connected by a passage 72 in the cylinder and passages 73 and 74 in the rear cylinder head 18 and the valve box cover 42, the passage 74 communicating with a recess 75 in the rear face of the valve box cover. The recess 75 communicates with an annular chamber 76 surrounding the front valve seat 49. A circular recess 77 in the front face of the valve box 43 communicates with the recess 75 so that adequate flow of pressure fluid to the chamber 76 is assured. Thus pressure fluid may flow from the supply pipe through passages 69, 70, 71, 72, 73 and 74, recesses 75, 77 and annular chamber 76 and through the restricted annular space about the outer periphery of the valve to the valve chamber 47. Formed in the walls of the cylinder bore substantially midway between the ends of the cylinder are exhaust grooves 79 communicating with a chamber 80 with which exhaust ports 81 in turn communicate. Threadedly secured at 82 to the center exhaust port is a hose 83 for conducting cleansing fluid to the drill hole to blow away the cuttings in the manner well known to those skilled in the art.

The drill parts above described are held together by a U-bolt 85 which is seated at its rear portion in a transverse groove 86 on the rear

head block 41 and has its leg portions 87, 87 extending longitudinally in parallelism along the sides of the motor cylinder and passing through openings 88 in the lateral lugs of a front collar 89. The chuck housing 35 has an enlarged rearward bore 90 which receives the integral front head 8 of the motor cylinder and the chuck housing is formed with a rearward annular flange 91 which is held by the collar 89 tightly against the front end of the motor cylinder. Threaded on the forward ends of the legs of the U-bolt are tightening nuts 92, 92. Thus when the U-bolt is tightened by the nuts 92, the chuck housing is firmly secured to the front end of the motor cylinder and the rear cylinder head 13, the valve box parts and the rear head block are firmly secured to the rear end of the motor cylinder.

In this illustrative construction, formed integral with the rear head block 41, is a handle 93 having a grasping portion 94, and the operator may grasp the grasping portion of the handle to manipulate the drill during the drilling operation. Formed in the grasping portion of this handle is a lubricant reservoir 95 provided with a suitable filler plug 96, and this reservoir is connected by a restricted passage 97 in the handle with a passage 98 in the valve box 43, and a restricted shallow groove 99 connects the passage 98 with the annular chamber 76. During operation of the rock drill, pressure fluid may flow from the annular chamber 76 through the restricted groove 99 and passages 98 and 97 to the lubricant reservoir 95 wherein the pressure fluid may act on the surface of the lubricant. During operation of the drilling motor, fluctuations in pressure occur in the chamber 76 so that lubricant may intermittently flow from the lubricant reservoir to the valve chamber to lubricate the motor parts.

The general mode of operation of the improved rock drill is as follows: Pressure fluid may be supplied to the supply pipe 63 under the control of any conventional throttle valve and pressure fluid may flow through the passages 69, 70, 71, 72, 73 and 74 and the recesses 75 and 77 to the annular chamber 76, and thence through the restricted metering space about the valve to the opposite ends of the valve chamber 41. When the fluid distributing valve 48 is in its forward position against the front seat 49, as shown in Fig. 2, pressure fluid may flow from the valve chamber 47 transversely past the rear valve seat 50 at the rear side of the valve and through the axial passage 54 to the recess 55, and thence through passages 57, 58, 59 and 60 and ports 61 to the front end of the cylinder bore at the forward side of the piston head. The pressure fluid acting on the front pressure area on the piston head moves the piston rearwardly to effect its return stroke. As the piston moves rearwardly, the leading edge of the piston head first overruns the exhaust grooves 79, and as the piston continues to move rearwardly, the pressure trapped in the rear end of the cylinder bore is compressed by the piston. When the following edge of the piston head overruns the exhaust grooves 79, the front end of the cylinder bore is connected to exhaust, thereby causing the pressure in the passages 60, 59, 58 and 57 and in the recess 55 and axial passage 54 substantially to drop, and the compressed fluid in the rear end of the cylinder bore acts through the axial passage 51 on the lower face of the valve 48 to throw the valve quickly rearwardly against the oppos-

ing reduced pressure from the position shown in Fig. 2 to the position shown in Fig. 4. When the valve is in the position shown in Fig. 4, against the rear valve seat 50, pressure fluid may flow from the valve chamber transversely past the forward face of the valve and through axial passage 51 and passages 52 in the rifle bar to the rear end of the cylinder bore. Concurrently, pressure fluid flows through the axial passage 53 in the rifle bar to the piston chamber 13. The pressure fluid acting on the effective rear pressure area of the motor piston moves the piston forwardly to effect its working stroke, i. e., to deliver an impact blow on the shank of the drill steel. During forward piston movement, the leading edge of the piston head first overruns the exhaust grooves 79 so that the fluid trapped in the front end of the cylinder bore is compressed by the piston. As the piston moves forwardly, the following edge of the piston head overruns the exhaust grooves 79, connecting the rear end of the cylinder bore to exhaust; and as a result, the pressure in the valve chamber at the forward side of the valve is substantially reduced. As the piston continues to move forwardly, the fluid compressed by the piston in the front end of the cylinder bore builds up in the passages 60, 59, 58 and 57 and in the recess 55 and axial passage 54, thereby quickly throwing the valve forwardly against the opposing reduced pressure from its position shown in Fig. 4 to its original position shown in Fig. 2. As the opposing pressures acting on the valve are substantially balanced before the piston overruns the exhaust port, a very slight degree of compression in the cylinder ends will throw the valve. The operations above described are rapidly successively repeated during normal operation of the motor.

During forward piston movement, the ratchet roller 27 automatically releases, permitting the rifle bar 15 to rotate so that the motor piston moves forwardly without rotation to deliver an unimpeded blow on the shank of the drill steel. When the motor piston moves rearwardly, the ratchet roller 27 automatically grips the surfaces of the members 20 and 22 to hold the rifle bar against rotation so that as the piston moves rearwardly, it is rotated by the spiral grooves of the rifle bar. Rotation of the piston is transmitted through the straight grooves 31 on the piston striking bar and the straight lugs 32 to the chuck sleeve 33 and through the chuck bushing 37 to the drill steel. The projections 38 on the rotatable chuck bushing 37 engage the opposed flat sides of the square body of the drill steel to rotate the latter with the chuck bushing. During operation of the motor, lubricant is automatically supplied from the lubricant reservoir to the pressure chamber 76 and thence through the ports and passages to the moving parts of the motor.

As a result of this invention an improved plug drill is provided having automatic means for rotating the drill steel. It will further be evident that by the provision of the improved fluid distribution means and the associated steel rotation means, an improved rock drill is provided which is not only relatively simple and rugged, but which is also more efficient in operation. The novel arrangement of the motor and chuck parts together with the improved U-bolt structure for holding the parts together, results in greater ease of assembly and dismantling of the drill, and simplicity in construction. These and other

modes of use and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a rock drill, the combination comprising a motor cylinder having a bore, a hammer piston reciprocable in said cylinder bore and adapted to actuate percussively a drill steel, fluid distribution means for the cylinder for effecting flow of motive fluid with respect to said bore to effect reciprocation of said piston, and means operated by said piston for intermittently rotating the drill steel and including a rotatable rifle bar having spiral grooves in sliding interlocking connection with said piston and an intermittent gripping device for controlling rifle bar rotation, said fluid distribution means including fluid conducting passages in said rotatable rifle bar and communicating with said cylinder bore.

2. In a rock drill, the combination comprising a motor cylinder having a bore, a hammer piston reciprocable in said cylinder bore and adapted to actuate percussively a drill steel, fluid distribution means for the cylinder for effecting flow of motive fluid with respect to said bore to effect reciprocation of said piston, and means operated by said piston for intermittently rotating the drill steel and including a rifle bar having spiral grooves in sliding interlocking connection with said piston and an intermittent gripping device for controlling rifle bar rotation, said piston having an axial chamber closed at one end for receiving said rifle bar, said fluid distribution means including fluid conducting passages in said rotatable rifle bar and communicating with said cylinder bore, and also including an axial passage in said rifle bar for conducting pressure fluid to said piston chamber.

3. In a rock drill, the combination comprising a motor cylinder, a piston reciprocable in said cylinder and adapted to actuate percussively a drill steel, fluid distribution means for supplying motive fluid to said cylinder to effect reciprocation of said piston and including a valve box aligned with said cylinder and having a valve chamber, and drill steel rotation mechanism operated by said piston and including an intermittent gripping device located forwardly of said valve box and including a rotatable rifle bar having a sliding interlocking connection with said piston, said valve box having a forward cylindrical portion on which the rearward portion of said rifle bar is rotatably journaled.

4. In a rock drill, the combination comprising a motor cylinder having a bore, a piston reciprocable in said cylinder bore and adapted to actuate percussively a drill steel, fluid distribution means for supplying motive fluid to said cylinder bore to effect reciprocation of said piston and including a valve box aligned with said cylinder and having a valve chamber, and drill steel rotation mechanism operated by said piston and including a rotatable rifle bar having a sliding interlocking connection with said piston, said valve box having a forward cylindrical portion on which said rifle bar is journaled, and said fluid distribution means including fluid conduct-

ing passages in said cylindrical portion and in said rifle bar and communicating with said cylinder bore.

5. In a rock drill, the combination comprising a motor cylinder having a rear head, said head having an axial bore and an enlarged chamber rearwardly of said bore, a valve box having a valve chamber and said valve box arranged in alignment with said cylinder rearwardly of said head, said valve box having a cylindrical projection extending forwardly into said head chamber, and drill steel rotation mechanism including an intermittent gripping device having a rotatable member, said rotation mechanism also including a rotatable rifle bar projecting through said head bore and having a portion journaled therein, said rifle bar having sliding interlocking connection with said piston, said rotatable member secured to and rotatable with said rifle bar and arranged in said head chamber and journaled for rotation on said valve box projection.

6. In a rock drill, the combination comprising a motor cylinder having a rear head, said head having an axial bore and an enlarged chamber rearwardly of said bore, a valve box having a valve chamber and said valve box arranged in alignment with said cylinder rearwardly of said head, said valve box having a cylindrical projection extending forwardly into said head chamber, drill steel rotation mechanism including an intermittent gripping device having a rotatable member, said rotation mechanism also including a rotatable rifle bar projecting through said head bore and having a portion journaled therein, said rifle bar having sliding interlocking connection with said piston, said rotatable member secured to and rotatable with said rifle bar and arranged in said head chamber and journaled on said valve box projection, and means for supplying pressure fluid from said valve chamber to said motor cylinder including communicating fluid conducting passages in said cylindrical projection and in said rifle bar, and said passage in said rifle bar communicating with said cylinder.

7. In a rock drill, the combination comprising a motor cylinder having a bore, a piston reciprocable in said cylinder bore and adapted to actuate percussively a drill steel, fluid distribution means for effecting supply of pressure fluid to said cylinder bore to effect reciprocation of said piston, and drill steel rotation means including a grooved bar having sliding interlocking relation with said piston and an associated intermittent gripping device, said fluid distribution means including a fluid conducting passage in said grooved bar and communicating with said cylinder bore.

8. In a rock drill, the combination comprising a motor cylinder having a bore, a hammer piston reciprocable in said cylinder bore and adapted to actuate percussively a drill steel, a rear head for said cylinder bore having a rear chamber and a forward axial bore, a valve box arranged rearwardly of said head and closing the rear side of said head-chamber, said valve box having a valve chamber containing a fluid distributing valve for controlling flow of pressure fluid to the opposite ends of said cylinder bore, and drill steel rotation mechanism operated by said piston including an intermittent grip mechanism distinct from said distributing valve and arranged in said head-chamber and a rifle bar having its rotation controlled by said grip mecha-

nism and extending forwardly through said head-bore into sliding interlocking relation with said piston.

9. In a rock drill, the combination comprising a motor cylinder having a bore, a hammer piston reciprocable in said cylinder and adapted to actuate percussively a drill steel, a rear head for said cylinder bore having a rear chamber and a forward axial bore, a valve box arranged rearwardly of said head and closing the rear side of said head-chamber, said valve box having a valve chamber containing a fluid distributing valve for controlling flow of pressure fluid to the opposite ends of said cylinder bore, and drill steel rotation mechanism operated by said piston including an intermittent grip mechanism arranged in said head chamber and a rifle bar having its rotation controlled by said grip mechanism and extending forwardly through said head-bore into sliding interlocking relation with said piston, and fluid conducting passages controlled by said valve including passages extending from said valve chamber forwardly through said valve box, and through the intermittent grip mechanism, rear head and rifle bar to the rear end of the cylinder bore.

10. In a rock drill, the combination comprising a motor cylinder having a bore, a hammer piston reciprocable in said cylinder bore and adapted to actuate percussively a drill steel, fluid distribution means for said cylinder for effecting the flow of motive fluid with respect to said cylinder bore to effect reciprocation of said piston, means operated by said piston for intermittently rotating the drill steel and including a rifle bar having spiral grooves in sliding interlocking connection with said piston and an intermittent gripping device for controlling rifle bar rotation, said fluid distribution means including a fluid conducting passage extending axially through said rifle bar and also including fluid conducting passages in said rifle bar exteriorly of said axial passage and communicating with the rear end of said cylinder bore at points rearwardly of the front end of said rifle bar.

11. In a rock drill, the combination comprising a motor cylinder having a hollow rear head, a hammer piston reciprocable in said cylinder and adapted to actuate percussively a drill steel, fluid distribution means for said motor cylinder for effecting fluid supply thereto to effect reciprocation of said piston and including a valve box aligned with said cylinder and having a valve chamber, a fluid distributing valve arranged in said valve chamber, said valve box including cooperating front and rear plates, said front plate having a forward cylindrical projection extending into said rear head, and a drill steel rotation mechanism operated by said piston and including an intermittent gripping device arranged within said rear cylinder head in advance of said front plate and having an intermittently rotatable element thereof journaled for

rotation on said forward projection and a rifle bar secured to said element and having sliding interlocking connection with said piston.

12. In a rock drill, the combination comprising a motor cylinder having a hollow rear head, a hammer piston reciprocable in said cylinder and adapted to actuate percussively a drill steel, fluid distribution means for said motor cylinder for effecting fluid supply thereto to effect reciprocation of said piston and including a valve box aligned with said cylinder and having a valve chamber, a fluid distributing valve arranged in said valve chamber, said valve box including cooperating front and rear plates, said front plate having a forward cylindrical projection extending into said rear head, and a drill steel rotation mechanism operated by said piston and including an intermittent gripping device arranged within said rear cylinder head in advance of said front plate and having an element thereof journaled on said forward projection and a rifle bar secured to said element and having sliding interlocking connection with said piston, said fluid distribution means including a fluid conducting passage extending through said forward projection and a cooperating passage in said element of said intermittent gripping device, said latter passage having communication with said cylinder.
